UNITED STATES PATENT OFFICE.

LOUIS GODDU, OF WINCHESTER, ASSIGNOR TO THE MCKAY METALLIC
FASTENING ASSOCIATION, OF BOSTON, MASSACHUSETTS.

MACHINE FOR MAKING STRING-NAILS.

SPECIFICATION forming part of Letters Patent No. 240,119, dated April 12, 1881.

Application filed February 11, 1881. (No model.)

To all whom it may concern:

Be it known that I, LOUIS GODDU, of Winchester, county of Middlesex, State of Massachusetts, have invented an Improvement in Machines for Making String-Nails, of which the following description, in connection with the accompanying drawings, is a specification.

This invention relates to mechanism for making string-nails for boot and shoe work, the 10 said machine making, as herein shown, string-nails from a wire. The string-nails will be wound on a spool or reel, as in United States Patent No. 216,789, dated June 24, 1879, granted to me, to which reference may be had, and 15 it is upon that class of machine that this present invention is an improvement. In that patent the heads of the string-nails were made by a setter or blade carried by a vibrating lever; but in this my present invention, instead of 20 the lever and setter, I employ a notched disk, which enables me to make from a wire of a given size a nail with a larger and more perfect head.

In this invention I have greatly simplified 25 the construction of the mechanism as compared with my patented machine, making it more rapid in operation and stronger and more certain in action. I have arranged the wire-feeding devices to turn about horizontal axes, 30 have connected the wire-clamping dies with the upper ends of long levers which open and close like nippers, and have connected with a rocker-shaft a notched wire-cutting and head-upsetting disk, which may be readily ground 35 as it is worn away.

Figure 1 represents, in left hand side elevation, a string-nail-making machine embodying my invention; Fig. 2, a vertical cross-section on the dotted line xx . Fig. 3 is a partial right-hand side view of the said machine, the top of the lower and the bottom of the upper feed-wheel being broken out, one of the dies being in section on the dotted line yy , Fig. 5. Fig. 4 is a detail of the rear side of a slotted washer placed on the shaft which carries the head-upsetting disk, the said washer showing an annular series of teeth to be forced into engagement with a like annular series of notches made at the end of a rocking sleeve, through

which the bolt carrying the washer is extended. 50 Fig. 5 is a top view of the wire-clamping dies and part of the ends of the jaws with which they are connected; Fig. 6, a face view of one of the said dies. Fig. 7 is a side elevation of the upsetting-disk. Fig. 8 is a detail showing 55 the wedge at the end of the hand-lever employed to cause the loose belt-pulley to be forced at the proper times in close contact with the fly-wheel fast on the main driving-shaft, so as to rotate the said shaft and operate the 60 machine. Fig. 9 is an edge view of the lower or main feed-wheel, and Fig. 10 is an end view of the sleeve g^3 , in contact with which the washer h is forced.

The main frame-work A of the machine will 65 be of proper shape and strength to support the working parts. The main shaft B has fixed to it the fly-wheel C, the two hub-cams D E, and the lever-moving disk D^2 , provided with studs or rolls $a b$, that during the rotation 70 of the said disk and shaft B act on the wings $a^2 a^3$, (see Fig. 2,) having shanks extended through the levers F F', pivoted at F^2 , and carrying at their upper ends the wire-clamping dies $c e$, the said dies being attached by bolts 75 23. The shanks of the wings $a^2 a^3$ are held in the levers F F' by the set-screws 4, and are made adjustable horizontally by the adjusting devices 5, (shown as threaded bolts,) the adjustment of the wings with relation to the jaws 80 enabling the dies to be closed together properly, notwithstanding variations in their width. The jaws are opened and dies separated by the spring G when the wire is being fed, suitable lugs, $d d'$, on the jaws meeting adjustable stops 85 $d^2 d^3$, controlling the distance between the separated dies and the upper ends of the levers F F'.

The hub-cam D receives a stud, 6, or a roller thereon, connected with the lower end of a sector-toothed feed-operating lever, f , having its fulcrum at f' , and engaged with the toothed wheel f^2 on the shaft f^3 , which is rocked by it, and which at its other end (see Fig. 3) has connected with it a pawl-carrying disk, f^4 , provided with a spring-controlled pawl, 8, which engages the teeth of a ratchet-wheel, f^5 , (see Figs. 3 and 9,) connected with or forming part 90 95

of the lowermost feed-wheel, n , having an annular and preferably corrugated groove, 30, to receive and firmly engage the wire w , to be formed into string-nails sn . This lever f and pawl-and-ratchet mechanism just referred to impart to the lowermost feed-wheel, n , an intermitting movement for the proper distance, according to the length of each nail to be produced from the wire w .

The uppermost feed-wheel, n^2 , or that which acts upon the wire to press it firmly on the lower feed-roller, n , with sufficient force to insure the forward movement of the wire w , has an annular groove in its periphery, as shown in Fig. 3, where a part of the periphery of the said roll is broken out. The axis 14 of this wheel n^2 is carried by an arm, n^3 , secured in place by screw n^4 , and the wheel mounted loosely thereon is simply a pressure-wheel, rotated by the wire w as the latter is moved by the wheel n . The wire w is led from a suitable reel or coil through the guides 12 13.

The hub-cam E receives a stud, 7, or a roll thereon, connected with the lower end of the vibrating sector-lever g , pivoted at g' . This sector-lever engages a toothed sector, g^2 , connected with or forming part of a long sleeve, g^3 , extended through a bearing, g^4 , forming part of the frame-work A , as in Fig. 2. The forward end of the sleeve which is made to rock in the said bearing, is provided with a radial series of teeth and notches, 32, Fig. 10, just such as represented by the series of teeth and notches 16 at the rear side of the washer h , (see Fig. 4,) the radial series of teeth and notches of the sleeve and of the washer coming together, as shown at Fig. 2, and so engaging each with the other as to insure the movement of the washer with the sleeve without slipping after the nut h^3 on the headed bolt h^4 shall have pressed the cutting and head-upsetting disk against the washer and the latter firmly against the end of the said sleeve. The washer is slotted at h^2 to receive the pin 18, (see Fig. 2,) extended backward from the cutting-disk i , so that the latter is moved positively with the said sleeve, washer, and bolt h^4 . The shoulder 19 of the cutter, by the movement of the sleeve in one direction, is caused to cut into the uppermost portion of the wire w , exposed between the dies $c e$, (see Fig. 5,) and raise up some of the periphery of the wire and crowd such part back into the head-forming cavities 20 of the said dies, (see Fig. 6,) thus shaping the part of the metal so disturbed or shoved back on the main body of the wire to form a suitable head with a beveled under side.

The portion 22 of each die, immediately at the rear of the head-forming cavities, is corrugated or grooved to corrugate or notch the shank of the nail just below its head as the dies are closed on the wire w by the levers $F F'$. The transverse notch 33 (see Figs. 5 and 6) in the dies $c e$ permits the cutting-disk i to dip into the wire, w , exposed in the said notch.

The ends of the dies beyond the said head-forming cavity 20 (see right of Fig. 6) are suitably cut at 23 to receive and not change the shape of the nail-head as the dies are next closed, and a head is being formed for a succeeding nail of the series of string-nails. The same cut that forms the head for a nail forms the point for the nail headed at the next preceding action of the dies and cutting-disk. The string-nails will pass from the dies through a guide, 25, thence over a yielding take-up spring, 26, to a reel, on which it will be wound, as in the patent referred to.

On the shaft B is a loose belt-pulley, k , having its outer side face made conical to fit a conical seat in the fly-wheel C , fast on the shaft B , when the said pulley is forced laterally against the fly-wheel. The pulley k or its hub 36 has placed against it a loose sleeve, 37, on shaft B , (see Fig. 8,) having a lug, 38, against which and between said lug and the stationary frame A works the wedge k^2 , connected with the hand-lever k^3 , having its fulcrum at k^4 , the movement of the wedge k^2 in the direction of the arms on it, Fig. 8, forcing the sleeve 37, hub 36, and loose wheel k firmly against the fly-wheel fixed on the shaft B , thus rotating the said shaft. This clutch device is not herein claimed, as it is old in other machines. The guides 12 13 straighten the wire. The upper ends of the levers $F F'$ are notched, as at p , Fig. 5, to receive teeth at the backs of the said dies to prevent the latter slipping.

I claim—

1. In a machine for making string-nails from wire, a pair of dies having head-forming cavities and notched transversely to expose the upper portion of the wire held in the said dies, combined with the oscillating cutting-disk adapted to cut into the exposed part of the said wire to form a point for one nail, and force that portion of the wire partially separated from the main body of the wire in the formation of the said point into the head-forming cavities of the said dies, substantially as described.

2. In combination with the feeding mechanism for the wire, and guides to keep it straight, the dies provided with head-forming cavities and notched transversely to expose the body of the wire to the action of the cutting-disk, the levers $F F'$ to move the said dies, and the disk-cutter to cut into the said wire held by the said dies and form the point for one and the head for another nail, substantially as described.

3. The levers $F F'$ and their dies $c e$, and the separate wings, combined with the rolls or studs to act on the said wings and operate the said levers to close the dies, substantially as described.

4. The levers $F F'$ and their dies, and spring to move the levers to separate the dies, combined with the lugs d and stops d^2 , substantially as described.

130

5. The cutter *i* and washer, and oscillating sleeve and bolt to hold the cutter and washer firmly in the sleeve, and the sector, combined with means to move the said sector, and with 5 the dies *c e*, substantially as described.

6. The feeding-wheel *n*, ratchet-wheel *f⁹*, and pivot and pawl carrier, and wheel *n²*, combined with the shaft *f³*, toothed gear *f²*, and means to impart to it and the said toothed

wheel, shaft, and pawl-carrier a reciprocating 10 motion, substantially as described.

In testimony whereof I have signed my name to this specification in the presence of two subscribing witnesses.

LOUIS GODDU.
